[57] CLAIM

The ornamental design for a keypad and speaker grille
portion of a portable two-way radio, as shown and
described.

DESCRIPTION

FIG. 1 is a front, top, and left side perspective view of
a keypad and speaker grille portion of a portable two-
way radio showing our new design; and,

FIG. 2 is a front elevational view.

The broken line showing of the two-way portable radio
is for illustrative purposes only and forms no part of the
claimed design.
